LIQUID-GAS CONTACT APPARATUS

William J. Beringer, Dayton, Ohio, assignor to
Aqua-Therm, Inc., Dayton, Ohio, a corporation
of Ohio

Application April 1, 1950, Serial No. 153,413

2 Claims. (Cl. 183—14)

1

This invention relates to liquid-gas contact apparatus.

More particularly is the invention concerned with liquid-gas contact in a packing bed as heretofore known and used in water cooling, air scrubbing and like installations. Prior art devices of this kind have had distinct and recognized practical limitations as to the temperature differential which can be achieved in water cooling and as to the degree of suspended solid matter which can be removed from a gas. Contributing to such limitation has been the difficulty of obtaining maximum liquid-gas contact in the bed as well as inefficient liquid distribution over the bed. Further, prior art devices have suffered from undue complication and excessive size, adding to their cost of manufacture and precluding the incorporation of such features as multiple utility and portability.

It is an object of this invention to present a liquid-gas contact device in which the essential elements thereof are closely and compactly arranged in such wise that they may if desired be built into a small, portable and relatively light weight unit.

Another object of the invention is to introduce in liquid-gas contact devices a new high level of performance resulting from use of a saddle type packing bed in combination with a novel liquid distribution system for realizing the greatest advantages from such bed.

A further object of the invention is to achieve through a combination as noted above an efficiency making possible direct air conditioning thereby.

Still another object of the invention is to present a basic construction, as set forth, applicable selectively to water cooling, air scrubbing, air conditioning and like work.

A still further object of the invention is to present a device of the kind described particularly characterized in that it has no moving parts, imposes no temperature limitations, has a low pressure drop, requires but small floor space and low head room, is simple to operate and maintain and which may be supplied with a wide range of capacities, shapes and construction materials.

Other objects and structural details of the invention will appear from the following description when read in connection with the accompanying drawings, wherein:

Fig. 1 is a view in perspective, partly broken away, of a liquid-gas contact device in accordance with the instant invention.

Fig. 2 is a view in cross section, taken substantially along the line 2—2 of Fig. 1;

2

Fig. 3 is a detail view of a packing element;
Fig. 4 is an installation diagram, illustrating
the device of the invention as operating to cool
and condition air;

5 Fig. 5 is a view similar to Fig. 4, illustrating
the device as operating to cool water; and
Fig. 6 is a view similar to Figs. 4 and 5, showing
the device as operating to scrub or clean gases
of obnoxious fumes and foreign matter.

10 In its illustrated embodiment, the liquid-gas
contact device of the invention, comprises, as
shown in Figs. 1 and 2, a casing 10 the top of
which is shown as being open since ducting and
15 conduits for the conduct of the liquid and gas
communicate therewith. In the bottom of the
casing is an upstanding partition wall 11 divid-
ing the lower end of the casing into a blower
20 compartment 12 and a sump 13. A gas inlet 14
communicates with the compartment 12 and a
liquid outlet 15 communicates with the sump
13. A motor driven blower 16, of a known com-
mercially available kind, is mounted in the com-
25 partment 12 to draw gas in through the inlet
14 and discharge it through an exit opening 17
across the sump 13 and upward in the casing.
Disposed above the blower 16 and defining a top
30 wall of the compartment 12 is a plate or baffle
18 fastened as by welding to one wall of the
casing 10 and extending toward, but terminating
short of the opposite wall. The plate 18 is in-
clined for a deflection of descending liquid out
35 of the compartment 12 and into the sump 13.
Above the plate 18 there are secured to the
side walls of the casing 10 angle pieces 19 pro-
viding a mounting for a grill sheet 21 of ex-
35 panded metal. The grill 21 supports a packing
bed 22 made up of a large number of saddle
shaped elements 23, one of which is shown in
detail in Fig. 3. The elements 23 are hard,
smooth surfaced objects made of any suitable
40 inert material, for example chemical stoneware.
All of the surfaces of the saddle elements are
curved, there being no ledges or crevices to
catch and collect foreign material. In forming
45 the bed 22, the saddle elements are simply poured
into the casing upon the grill 21 to the desired
depth, filling the transverse dimensions of the
casing. The saddle elements accordingly occupy
50 random positions with respect to one another in
the bed and define a maze of interconnecting,
irregularly shaped chambers and passageways,
there being no account of the shape of the
saddle elements a high proportion of open space
55 in the bed as well as a very large contact area.
Depending upon the size of the saddle elements,
there may be from fifty to one hundred and fifty

or even more square feet of surface area in the bed per cubic foot of volume.

In overlying relation to the packing bed 22 is a series of distributor pans 24 which are generally U-shaped in cross section, being closed at their bottom and ends and having parallel up-standing side walls. The individual pans 24 extend from side to side of the casing where they are supported on angle pieces 25 and the series of pans extends from end to end of the casing, adjacent pans of the series being spaced apart for a flow of gas therebetween exteriorly of the pans. In the upper edges of each pan are V-cuts 26 spaced calibrated distances apart.

Seated on top of the pans 24 and extending transversely thereof from end to end of the casing is a relatively narrow trough 27 having in its bottom longitudinally spaced apart series of perforations 28, each arranged to overlie and communicate with a respective distributor pan 24. The trough 27 is supplied with liquid, as by the diagrammatically indicated conduit 29. The liquid may escape from the trough 27 through the openings 28 into the pans 24 under a hydrostatic pressure head which is a function of the rate of flow through conduit 29 and the size and number of the openings 28. As the pans 24 fill with liquid there is an overflow therefrom through the V-cuts 26, the overflow forming small independent streams which run down the sides of the pans 24 and on to the top of the packing bed 22. By reason of the arrangement of the distributor pans and V-cuts therein, there is accordingly formed a large number of liquid streams which descend upon and enter the packing bed at spaced points over the entire surface of the bed. There is a further distributive effect in the packing bed, wherein the saddle elements break up and intermingle the several streams with the result that there is a uniform and even wetting of the packing bed with no opportunity offered for the liquid to form and follow channels through the bed.

A pair of expanded metal grills 30 and 31 are arranged alongside the trough 27 on angle pieces 32 on the ends and sides of the casing 10. Saddle elements like the elements 23 are supported on the grills 30 and 31 and in effect make up a single packing bed 33. The bed 33 is thus mounted out of contact with the liquid but in the path of flow of the gas out of the casing. It accordingly may function as a mist or drift inhibitor, collecting water particles carried by the gas stream and allowing them to drip down into the pans 24 or directly upon the packing bed 22.

In the operation of the device, therefore, the liquid and gas are brought into intimate physical contact in the packing bed 22, with the gas flowing generally upward therein and the liquid flowing generally downward. The gas distributes itself evenly over the area of the packing bed, in entering the bottom thereof, but in its passage through the bed is broken up into a multitude of small ribbon-like currents, and, as such, comes into contact successively with small countercurrent streams of liquid which travel in thin films over each saddle element 23. Thus a large surface area of gas comes into intimate contact with a large surface area of liquid under conditions of low surface tension. Under these favorable contact conditions, the desired function of the device is carried out with a high efficiency. Thus in water cooling, the obtaining of maximum contact area between the heated or warm water and the relatively cooler air provides for maximum

absorption of water vapors by the air and a corresponding high rate of cooling of the water. Similarly, in air conditioning the moist warm air yields its vapor content readily to the counter flowing relatively cool water with a corresponding rapid drying and reduction in temperature of the air. In air scrubbing or cleaning the counterflowing liquid irrigates the packing bed which can be described as a labyrinth of smoothly streams of liquid with a countercurrent flow of turbulent air or gas streams. As the direction of each small ribbon of gas is changed by approximately forty-five degrees, which occurs from eight to thirty-two times per foot of travel and in random directions, air borne solids in the gas stream tend to continue in the prior direction whereupon they impinge on and cling to the liquid film flowing over the packing pieces. A similar mode of action will take place in the use of the device as an absorber for by-product recovery.

In the system diagrams of Figs. 4, 5 and 6, Fig. 4 illustrates the liquid-gas contact device in a typical air conditioning system. Indicated at 34 therein, the gas inlet 14 of the device communicates with a conduit 35 leading from a space 36 to be cooled. Another conduit 37 leads back to the space 36 and communicates with the top of the device to receive the air emerging from the dry bed 33. A liquid inlet conduit 38 communicates with the trough 27 while a liquid outlet conduit 39 is connected to the sump outlet 15. Moist warm air is drawn from the space 35 through conduit 35 while cool water or other liquid enters the device by way of conduit 33. Within the packing bed 22 the air and liquid achieve a pervading contact with one another with the result that the air gives up its moisture and heat to the liquid and flows to conduit 37 for delivery back to the space 36 in a cool dry state. The now warm liquid drops into the sump 13 and is drawn off through conduit 39, it being understood that suitable pumping means will be supplied for this purpose. The liquid may circulate in a closed system, in which case conduit 39 will be connected to conduit 38 by appropriate liquid cooling means. Alternatively, the conduit 39 may discharge directly to drain, while conduit 36 communicates with a source of fresh water, as the city supply line.

In Fig. 5, the device is illustrated as used for water cooling purposes. There will be, in this instance, an applied heat load across a pair of conduits 41 and 42 and a water jacket 43 through which cool water is circulated at a rate to obtain a predetermined reduction in the heat load. The water coolant circulates in a closed system, the water entering the jacket 43 by way of a conduit 44 and leaving by a conduit 45. The conduit 44, which will have a pump 46 interposed therein, is connected to the sump outlet 15 of the liquid-gas contact device, here indicated at 34a. The conduit 45 is connected to the top of the device to discharge into the trough 27. The air inlet 14 of the device is connected to atmosphere, as by a conduit 47. The air discharge, from packing bed 33, occurs through a conduit 48. In the operation of this system, water warmed by its passage through the jacket 43 is conducted by conduit 45 to the trough 27 from which it is distributed over the packing bed 22. Counterflowing, relatively cool, air is encountered in the bed with the result that the air absorbs moisture from the water, effecting cooling thereof. The cooled water descends to the sump 13 and is returned by way

of conduit 44 to the jacket 43. The warmed, moist air discharges to atmosphere through conduit 48.

In Fig. 6, the liquid-gas contact device, here indicated at 34^b, is illustrated in an air or gas scrubbing system. A ventilator 49 is arranged to exhaust a given area under the influence of the blower 16, the ventilator being connected by a conduit 51 to the gas inlet 14 of the device 34^b. Above the packing bed 33 the device is connected by a conduit 52 venting to the atmosphere or returning for reuse in the exhaust area if desirable. Irrigating liquid is supplied the trough 27 by way of a conduit 53 while a conduit 54 carries off the liquid from the sump 13. Contaminated exhaust gases are conducted by conduit 51 to the packing bed 22 where they flow upward in contact with the irrigating liquid. Vaporous and solid matter in the gas is transferred in the bed to the liquid so that clean air emerges for discharge through the conduit 52. The contaminated liquid is drawn from the sump by way of conduit 54 which may if desired lead to an artificial setting pond whereby the irrigating liquid may be confined in a substantially closed circuit and reused.

With further regard to the construction and arrangement of the liquid-gas contact device, it will be noted that the internal structure thereof lends itself to a variety of installations. Thus it may, as in the illustrated instance, be contained in a metal casing in unitary package form. As such it is portable, easily shipped and handled and may be installed in any convenient location. For a permanent installation, there may be substituted for the casing 10, a brick or concrete block housing with the internal structure of the device being built into the housing. Either type of installation is in keeping with the high performance characteristics of the device, particularly as regards the cooling of high temperature liquids.

In connection with these performance characteristics, the instant invention makes easily feasible the handling of water cooling problems which heretofore were impracticable of solution on account of the size of the installation required and its corresponding cost. It may, for example, be desired to cool water flowing at one thousand gallons per minute from 130° F. to 90° F., using ambient air having a wet bulb temperature of 80° F. Utilizing a tower construction in accordance with the instant invention, the desired heat reduction can be achieved in a packing bed 22 eighteen inches in depth and a mist or drift elimination bed 33 three inches in depth, with an air volume flow somewhat greater than one hundred thousand cubic feet per minute. With an air velocity of three hundred feet per minute, the transverse dimensions of the packing beds would be approximately eighteen by twenty feet and the overall height of the tower about twelve feet. The exit air temperature under these conditions would be about 110° F. The relatively small size of the tower, considering the magnitude of the

problem involved, is made possible by the relatively small size of the contact bed 22 and this in turn is a function of the saddle packing in conjunction with the even and uniform distribution of water over the bed.

What is claimed is:

1. A liquid-gas contact device, including a casing open at the top thereof, a liquid inlet trough extending across the top of said casing, and having longitudinally spaced apart perforations in its bottom, a series of spaced apart liquid distributor pans in transverse underlying relation to said trough and positioned to receive liquid from respective perforations in said trough, a series of longitudinally spaced apart V-cuts in each said pans through which the liquid in the pans may overflow and drip downward in the casing, a bed of packing material beneath said distributor pans upon which the liquid drips in a plurality of streams at predetermined points over the area of the bed, said packing material comprising random positioned saddle shaped elements to accomplish a variable intermingling and numerous changes of direction of said liquid streams as they descend through the packing bed, a sump in the bottom of said casing to collect the liquid and an outlet from said sump, and means for directing a countercurrent of gas upwardly through said packing bed and thence between said pans for discharge out of the top of the casing, said gas current being constrained by said saddle elements to follow substantially the same flow path as said liquid streams but in a reverse direction.
2. A liquid-gas contact device, according to claim 1, characterized by a supplemental bed of packing material arranged in embracing relation to said trough, above said distributor pans through which said air current is discharged from the casing in non-contacting relation to the liquid.
